CLAIM

The ornamental design for a packaging material with surface pattern, as shown and described.

DESCRIPTION

The patent or application file contains at least one drawing executed in color. Copies of this patent or patent application with color drawings(s) will be provided by the Office upon request and payment of the necessary fee.

FIG. 1 is a perspective view of a packaging material with surface pattern, showing our new design;

FIG. 2 is an enlarged detail view of the circumscribed portion (dark circle) of FIG. 1 thereof;

FIG. 3 is a front view of FIG. 1 thereof;

FIG. 4 is a bottom view thereof;

FIG. 5 is a rear view thereof;

FIG. 6 is a top view thereof;

FIG. 7 is a left side view thereof; and,

FIG. 8 is a right side view thereof.

The broken lines are shown for the purpose of both designating an enlargement view and illustrating parts of the article. None of the broken lines form part of the claim.
